POCKET CALCULATING MACHINE

Aron M. Josepho, New York, N. Y.

Substituted for abandoned application Serial No.
239,797, November 10, 1938. This application
January 21, 1943, Serial No. 473,079

4 Claims. (Cl. 235—74)

My invention relates to calculating machines and more particularly to machines of pocket size type.

An object of the invention is to provide a calculating machine that can be used especially for calculation in addition and subtraction.

A further object of the invention is to provide means for memorizing the numerals used in making calculations in connection with my invention.

A further object of my invention is to provide means whereby a record can be had of the number of times the resetting bar had been set in the device comprising my invention.

Further objects of the invention will be seen as the description thereof proceeds.

Referring to the drawings:

Figure 1 is a plan view of the calculator device or machine showing a "memory" unit in open position.

Figure 2 shows the numeral entering registering dials of the calculating machine shown in Figure 1, with the upper cover removed, taken on the line 2—2, Figure 8. The dials, marked from zero to 9, are shown for clarity only with the zero.

Figure 3 is a section taken on the line 3—3 of Figure 8, said figure showing the totalizing dials, marked from zero to 9 but, for clarity only, showing the zero.

Figure 4 is a partial sectional view of the rear side of the device taken on the line 4—4, Figure 8, said view showing the single toothed finger for operating the totalizing dials.

Figure 5 is a view of the resetting mechanism for resetting the numeral entering registering dials, shown without markings, to zero setting.

Figure 6 is an enlarged view showing the manner for locking the numeral entering dials, shown without markings, into place, the purpose of which will be hereinafter described.

Figure 7 is a section taken on the line 7—1, Figure 6.

Figure 8 is a section taken on the line 8—8, Figure 6.

Figure 9 shows a partial sectional view through the memory unit of the machine.

Figure 10 is a diagrammatic view illustrating the manner the calculating machine is used for making calculations in addition.

Figure 11 is a partial section through the device showing the numeral entering registering dials and the totalizing dials. The numerals etched upon the surface of each dial run from zero to nine.

Figure 12 is a section through the device showing the relation of the numerals etched upon each dial. Note that the numerals of adjacent entering dials run in opposite direction.

5 While one dial has numerals etched thereon running in a clockwise direction, the other dial has numerals running in an anti-clockwise direction.

Fig. 13 is a face view in elevation of the resetting bar and three of the numeral total dials resetting gears.

Fig. 14 is a perspective view showing the driving pinions for operating the dials.

Referring to Figure 4, the numeral 20 represents the calculating machine proper. A cover 21 is set or mounted over a base plate 22. A second cover 23 is mounted over the first cover 21. As shown in Figure 1, the covers 21 and 23 are secured to the base plate 22 by means of 20 suitable screws 24 and 25 respectively.

The cover 21 has one row of visual openings 26, 27, 28, 29, 30, 31 and 32. The cover 23 has two rows of visual openings 26x, 27x, 28x, 29x, 30x, 31x and 32x; and also openings 26xx, 27xx, 28xx, 29xx, 30xx, 31xx and 32xx.

A set of knobs 33 are used for operating the machine. A resetting bar 34 is used to reset the numbers shown through the row of openings 26 to 32 inclusive. Another resetting bar 35 is used 30 to reset the numbers visible through the openings 26x to 32x inclusive, and also 26xx to 32xx inclusive.

The openings 26 to 32 inclusive are used for observing the sum totals. The openings 26x to 35 32x inclusive are used for observing calculations made in addition, and the viewing openings 26xx to 32xx inclusive are used for observing calculations made in subtraction. The knobs 33 are rotated clockwise for calculations in addition and 40 anti-clockwise for subtraction calculations.

A sliding bar 36 with markings thereon, said markings representing units, tens, hundreds, thousands, hundred thousands and millions is slidably mounted over the front portion of the 45 calculating machine. The sliding bar 36 is provided with visible openings 37 and 38, and is slid by means of the knob 39, see Fig. 1. The sliding bar is used for convenience in fixing the decimal point at the beginning of a calculation.

50 An L-shaped bracket 40 is attached to the right side of the machine and has a viewing opening 41. A ratchet wheel 42 with markings thereon from zero to 9 is operated by a flexible spring 43 which is attached to the end of the 55 resetting bar 35. As the wheel 42 has an equal

number of teeth corresponding to the markings thereon every time the resetting bar 35 is operated the wheel 42 is accordingly rotated through the medium of the spring 43 and in this manner a numerical record is obtained of the number of times that the resetting bar 35 is used.

On the right side of the calculating machine a "memory" unit 44 for memorizing numerals used in making multiplication and division is hingably mounted on a hinge 45. The memory unit is shown in open position in Figure 1, which unit comprises a pair of plates 46, having visible openings 48 and 49. A set of gear wheels 50 with markings thereon from zero to 9 are rotatably mounted within the plates 46 and 47.

Whenever a number has to be memorized by the user of the device, the knurled discs 50x are turned by the finger until the required number is shown through the visual openings 48 or 49. A resetting knob 51 having a gear 52 in mesh with the gears 50x is used for resetting the same to zero. (The "memory" unit described above is used to memorize numbers for multiplication and division calculations only.)

Referring to Figure 2 which illustrates a section through the numeral entering registering dials of the machine, the dials 53 are used for addition and the dials 54 are used for subtraction.

Referring to Figure 6 dials 53 are provided with teeth on their peripheries and they rotate on shafts 55. The numeral entering registering dials 54 are also provided with an equal number of teeth similar to dials 53. The dials 53 are rotatable on shafts 55, but are mounted thereon with enough friction to enable them to rotate with shafts 55. The dials 54 rotate on shafts 55, and their teeth mesh with the teeth upon the dials 53 so that when the dials 53 are rotated by the action of the shaft 55, the dials 54 are turned likewise.

The resetting bar 35 is provided with curved extensions 51. The dials 53 are conjoined to heart-shaped cams 58 (see Figure 5). When said cams 58 are moved from the position shown in Figure 5 then by a sliding movement of the resetting bar 35 in the direction shown by the arrow against the tension of the spring 59, the curved extensions 51 of the resetting bar 35 will contact the cams 58 and will rotate said cams 58 and with them the dials 53 respectively, to their original zero position. As the teeth of the dial 53 mesh with the teeth of the dial 54, the resetting operation upon the dials 53 will also reset the latter.

A set of hingably mounted fingers 60 hinging at 61 are located inside the cover 23. The hingably mounted fingers 60 are under pressure of the spring 62. The functions of the hingably mounted fingers 60 will be further described hereinafter.

The resetting bar 35 is slidably mounted inside the cover 23 and is guided by the screws 63 and 64.

Referring to Figure 3 which is a section through the totalizer unit of the machine, the totalizer dials 65 conform in appearance to a ten-point star with markings thereon respectively from zero to 9. The markings are arranged alternately in clockwise and counter-clockwise positions on adjacent dials.

A set of springs 66 are set over the corners of the star-shaped dials, said springs serving to hold said dials 65 in place, each of said springs being secured to a spring supporting member 67.

the latter being fastened upon the partition wall or plate 73.

At the rear of each of the totalizer dials there is a gear 68, mounted on each shaft 55, which is operated by rotation of the knobs 33 through the gears 68 and, where present in the train, gears 70. Each gear 68 in the row is securely attached to each shaft 55, the train of gears 69 and 70 being idlers, their sole purpose is to transfer the rotating operation of the knob 33 to the gear 68. The totalizer dials are so geared that one of said dials rotates in a clockwise direction while the adjacent dial turns in an anti-clockwise direction.

The totalizer dials 65 are secured to the shafts 55. The numeral entering registering dials 53 are loosely mounted on the shafts 55. The numeral entering registering dials 54 are also loosely mounted on the shafts 55. The dials 53 have teeth upon their circumference which are in mesh with the teeth upon the dials 54. There is enough friction between the shafts 55 and each of the dials 54 to cause the dials to turn with the shafts 55 when shafts 55 are rotated. Each of the shafts 55 has a hub 71 having a finger 72 fastened to it and each hub 71 is fastened to its respective shaft 55. The shafts 55 are rotatably mounted in plate 73 which is secured to the calculating machine proper by means of the screw 74.

The knobs 33 operate the train of gears 68 and 69, including gear 70, where present in the train, through the medium of the intermediate gear 76 and the shafts 55. In the train of gears wherein the gear 70 is missing, the intermediate gear 76 meshes directly with the gear 68, see Fig. 12. The shafts 55 are held in place by means of U-shaped brackets (not shown) secured to the base 22 by means of screws (not shown). The opposite end 76x of each of the shafts 55 turns in the L-shaped extensions 76 of the plate 73.

At the rear of the plate 73 (see Figure 4) and secured to the shafts 55 are toothed discs 80. A single toothed finger 81 is secured to each shaft 55 with the exception of the last shaft on the right of the device. Each finger 81 is positioned in such manner upon the shaft 55 as to contact any one tooth of a neighboring toothed disc 80 to the left of the device. It can be seen that while the shafts 55 make one complete revolution, each toothed finger 81 on one shaft will contact the toothed disc of an adjacent shaft only once in every revolution and will turn said disc one tenth of a revolution. This is what is termed the tens transfer. It will be understood that the toothed disc 80 has ten teeth upon its periphery.

The resetting bar 34 which has a slot 82 for accommodating gears 85 slides under the tension of spring 83. The resetting bar 34 comprises an upper toothed rack 83a and a lower toothed rack 84. A gear 85 is also secured to each of the shafts 55. The gear 85 in this case has eight teeth and is operated through the medium of the toothed racks 83a and 84. Each rack operating every second gear 85, the upper rack 83a operating one gear and the lower rack 84 operating a second gear etc. Said racks have ten teeth each. Thus when the totalizer dials 65 are at zero the gears 85 are released from the rack 83a and 84 and cannot be rotated as shown in Figure 4.

While the gears 85 are clear of the teeth of racks 83a and 84 the shafts 55 are free to rotate,

when operated by the knobs 33 and the train of gears 75, 70 where present, 69 and 68.

Operation—Addition

Referring to Figure 10 which illustrates the manner the calculating machine is used for the purpose of addition; for example, if a number 887 has to be added to the number 475 the knobs 33 marked as first, second and third are turned in succession (see Figure 10, position A) so that the visual openings 30x, 31x, 32x are registering the number 475. As the knobs 33 operate the train of gears 68 and 69, including gear 70, where present in the train, the totalizer dials 65 will register the same number 475 which number can be viewed through the visual openings 30, 31 and 32.

Position B also shows the number 475 retained by the totalizing dials 65 although the resetting bar 35 has been actuated to reset the numeral entering registering dials 53 to zero. Position B also shows the registering of the resetting bar 35 by means of the ratchet wheel 42 which shows that the resetting bar has been operated once.

Position C indicates the manner in which the number 887 is added to the number 475. In this case the knobs 33 are again rotated in succession as marked first, second and third until the numeral 887 can be viewed through the visual openings 30x, 31x, 32x. As the knobs 33 also rotate the totalizer dials 65, the visual openings 29, 30, 31 and 32 will show the total of both numbers which sum is 1362.

Subtraction

In the case of calculations made in subtraction, the numerals of the lower numeral entering registering dials 54 are used. For example, if a number 388 has to be subtracted from the number 475 first, the number 475 is registered by turning the knobs 33 clockwise as indicated in Figure 10, position A. Second, dials 53 are set to zero by sliding the resetting bar 35 as shown in position B in Figure 10. Third, the number 388 is registered by the lower number entering registering dials 54 by turning the knobs 33 in anti-clockwise direction in succession as indicated in Position C, Figure 11, first, second and third. The final result will be number 87.

The function of the fingers 60 is to lock the toothed dials 53 which are loosely mounted on the shafts 55 when the totalizer dials 65 which are secured to shafts 55 rotate from 9 to zero position and vice versa. This operation is required for the purpose of retaining the toothed dials 53 in their set positions. The fingers 60 are moved by the extension fingers 72 which are fastened on each of the hubs 71 which are secured to the shafts 55.

This application is based on my abandoned application, filed Nov. 10, 1938, Serial No. 239,797.

Having described my invention, what I claim and desire to secure by Letters Patent, is as follows:

1. A calculating device comprising: a row of rotatable shafts mounted in a holder, each shaft having one of a first set of dials fixed thereon and another dial of a second set frictionally

clutched thereon, all the dials having numerals thereon, a fixed index means to which a selected numeral on each of the dials is settable, means to rotate the dials on a shaft together to set up a value, tens transfer means operatively connecting the dials of the first set, a means for resetting the dials of the second set to zero, and means for locking the dials of the second set against rotation during the tens transfer of corresponding dials of the first set.

2. A calculating device comprising: two rows of shafts mounted in a holder, the shafts of one row each having one of a first set of dials fixed thereon and another dial of second set frictionally clutched thereon, the shafts of the first row being rotatable, all the dials having numerals thereon, a fixed index means to which a selected numeral on each of the dials is settable, a third set of dials mounted on each shaft of the second row of shafts and each having means engaged with means on each of a corresponding one of the dials of the second set, means to rotate the first set of dials together with the second and third set to set up a value, tens transfer means operatively connecting the dials of the first set, a means for re-setting the dials of the second set together with the dials of the third set to zero and means for locking the dials of the second set against rotation during tens transfer of corresponding dials of the first set.

3. A row of rotatable shafts mounted in a holder, each of the shafts having one of a first set of dials fixed thereon and another dial of a second set frictionally clutched thereon, all the dials having numerals thereon, means to rotate the dials on a shaft together to set up a value, means on the shafts for moving an adjacent shaft in tens transfer operation, and means to reset the second set of dials to zero, means for locking the dial of the second set during the tens transfer operation, the locking means during the tens transfer operation comprising, a hingably mounted lever for engaging means associated with a dial of the second set, and a cam on a shaft adjacent the lever for moving the lever into locking position during said operation.

4. A row of rotatable shafts mounted in a holder, each of the shafts having one of a first set of dials fixed thereon and another dial of a second set frictionally clutched thereon, all the dials having numerals thereon; means to rotate the dials on a shaft together to set up a value, said means comprising: alternate trains of gears having an odd number and even number of gears, and rotatable means for moving each train of gears, whereby alternate shafts are caused to rotate in a direction opposite to the direction of operation of the other shafts, means to reset the second set of dials to zero, means on the shafts for moving an adjacent shaft in tens transfer operation, means for locking the dial of the second set during the tens transfer operation, the locking means during the tens transfer operation comprising, a hingably mounted lever for engaging means associated with a dial of the second set, and a cam on a shaft adjacent the lever for moving the lever into locking position during said operation.
